2 SHEETS—SHEET 2.

UNITED STATES PATENT OFFICE.

IDA N. CAREY, OF TUSCARORA, NEVADA.

RAIL TIE AND FASTENING.

1,345,126.

Specification of Letters Patent. Patented June 29, 1920.

Application filed February 20, 1920. Serial No. 360,113.

To all whom it may concern:

Be it known that I, IDA N. CAREY, a citizen of the United States, residing at Tuscarora, in the county of Elko and State of Nevada, have invented certain new and useful Improvements in Rail Ties and Fastenings; and I do hereby declare the following, to be a full, clear, and exact description of the invention, such as will enable others skilled in the art to which it appertains to make and use the same.

This invention relates to certain new and useful improvements in rail tie and fastening therefor and resides in the provision of a concrete tie that is reinforced by a number of metallic plates and strips and is strong and durable.

The present invention is designed as an improvement on my rail tie and fastener covered by my United States Patent 1,132,437, issued March 16, 1915.

Another object of the invention resides in the provision of the rail tie and fastening upon which a rail will be securely held and prevented from moving to either side.

A further object of the invention resides in the provision of a rail tie and fastening including clamping members for engagement with the opposite sides of the rails to prevent spreading thereof either at the joint of the rail sections or between the joints.

A still further object of the invention resides in the provision of a rail tie and fastening of the above stated character which will be of simple construction and in which all of the parts will be securely connected and clamped together to increase the rigidity of the tie and prevent wear thereon due to constant pressure of the rail on the tie.

The invention has for a still further object, the provision of a rail tie and fastening of the character stated which will be of simple construction, reliable and efficient in operation and capable of being readily attached and detached relative to the tie.

The invention has for a still further object, the provision of a rail tie and fastening of the character stated which may be employed in connection with the conventional form of rails now in general use.

With the above and other objects in view, as will appear as the description proceeds, the invention consists in the novel construction, combination and arrangement of co-

operating elements as hereinafter more specifically set forth, claimed and pointed out in the accompanying drawings, in which:

Figure 1 is a plan view showing the track constructed with my improved ties and fastening.

Fig. 2 is a fragmentary longitudinal sectional view taken vertically through one of the ends of the tie, showing the fastening means in operative position and a rail 65 thereon.

Fig. 3 is a transverse sectional view, taken through one of the ends of the tie, showing the rail thereon in side elevation,

Fig. 4 is a perspective view of one end of 70 the tie, showing the members mounted thereon, and within which are to be engaged the rail clamping members,

Fig. 5 is a detail perspective view of the 75 rectangular rail supporting plate,

Fig. 6 is a detail perspective view of one 80 of the clamping members employed at the rail joint,

Fig. 7 is a detail perspective view of one 85 of the rail clamping members employed along the sections of the rails.

Referring more in detail to the drawings, in which similar reference characters designate corresponding parts throughout the several views, 1 indicates as an entirety the 85 concrete body portion of my improved tie, and which is provided upon its upper and lower faces with longitudinal channels 2 and 3, in which are mounted rectangular metallic plates 4 and 5. These channels 90 and plates extend the length of the tie and the plates are flush with the ends thereof. The outer faces of the plates are flush with the upper and lower faces of the body portion 1.

Formed adjacent to the ends of the tie in the side faces thereof are opposed vertical channels or recesses 6, designed to receive the side plate portions 7 of an approximately U-shaped bracket member 8 so that 100 the outer faces of the plate 7 are flush with the outer side faces of the tie. An opening 9 is formed in the body portion of the U-shaped member 8 intermediate the ends thereof and aligned with openings in the 105 plates 4 and 5. A bolt 10 having a square body portion is inserted through the opening 9 and aligned opening described and through a tubular member 11 of corresponding form and which is embedded in the tie 110

in such a manner as to aline with the opening described. The upper end of the bolt is rounded and threaded to receive the nut 12 which is turned thereon and countersunk 5 within the top plate 4. It will be understood the bolt may be reversed if desired so that the nut 12 will be upon the outer face of the body portion of the member 8 and beneath the tie.

10 The construction and arrangement of elements thus far described are similar in construction to the corresponding parts described in my Patent 1,132,437, issued March 16, 1915. The coöperation of these elements 15 with the other elements to be employed in building up the new tie and fastening herein described will be apparent as the description proceeds. The side plates 7 of the member 8 have laterally extending flanges 20 13 provided with apertures 14 and adapted to have engaged thereon the hook portions 17 formed at the opposite ends of the supporting plate 15 by bending the ends of said plate 15 downwardly and inwardly, as 25 shown in the drawings. The rail supporting plate 15 is also provided with upstanding flanges 16 provided with bolt openings 20 while the bolt openings 18 are formed in pairs in the body or bottom of the plate 15 30 to aline with the openings 14 in the flanges 15 and receive the fastening members 19.

To securely hold the rail in position upon the rail supporting plate 15, I have provided clamping members to be employed in pairs 35 and consisting of elongated rail web engaging strips 21 from the lower edges of which extend the central rail base engaging portions 22 having extended upstanding outer edges 23 which are parallel with the up- 40 standing flanges 16 of the plate 15 when the clamping members are in position, the upstanding outer edges or flanges 23 engaging the inner faces of the flanges 16 and having bolt openings 24 registering with the bolt 45 openings of the flanges 16 in order that bolts or other suitable securing members may be extended through the registering openings 20 and 24 to securely hold the clamping members in proper position. The clamping 50 members 21 extend along the web portions of the rails to either side of the ties and have bolt openings 25 adapted to register with the bolt openings through the web portions of the rails to draw the clamping 55 members into clamping engagement with the opposite faces of the rail web, with the upper edges 26 of the clamping members engaging the under face of the tread portions, of the rail, thereby completely inclosing the 60 web and base portions of the rail and preventing movement of the rail in either direction. These clamping members are adapted for use at the joints of the rail sections, the body portions or strips extending 65 to either side of the joint a sufficient distance

to securely hold the rail in proper position and strengthen the joint. The rail sections are designated by the numeral 27.

For securely clamping the rail sections 27 upon the ties between the rail joints, I have 70 provided rail clamping members 28 adapted to be arranged in pairs upon the opposite sides of the rail sections and in engagement with the web portions thereof with the upper edges 29 of the clamping members 28 75 engaging the under sides of the tread portions of the rail sections. The clamping members 28 are extended downwardly and outwardly from the lower edges 30 of the main portions thereof, to form the rail base 80 flange engaging portions 31 having their outer edges carried upwardly to form flanges 32 which are also extended slightly inwardly and parallel with the flanges 16 of the plate 15 in connection with which the clamping 85 members 28 are employed. The flanges 32 are provided with spaced bolt openings 33 registering with the bolt openings 20 of the flanges 16 to receive connecting bolts. Each clamping member 28 is provided with an 90 upstanding or inclined stay 34 extending upwardly on an incline from the point of connection of the portion 31 of the clamp with the flange 32 thereof to the main portion or web engaging portion of the clamp 28 at 95 a point above the center thereof, thereby strengthening the clamping member and retaining the main portion in clamping engagement with the web of the rail. The stay 34 is preferably located at a point between the bolt openings 33, thus bringing the reinforced or strengthened portion of the clamping member over the center of the tie.

From the foregoing, it will be apparent 105 that I have provided a rail tie and fastening which may be employed in connection with the conventional form of rail and will securely hold the rail fixed in proper position and form a solid support therefor, 110 all of the rail sections forming each rail of the track being retained in proper position with respect to one another and the opposite rails of the track prevented from spreading apart. It will furthermore be apparent 115 that it is unnecessary to provide clamping bolts for engagement through the web portions of the rails and the clamps arranged along the rail section. Furthermore bolts or other securing members may not be provided for engagement through the base portions of the rail sections as the rail sections 120 will be securely held in proper position upon the tie by the clamping members and rail supporting plates, as will be clearly apparent by referring to the drawings. In fact, the only bolts extended through the rail sections will be employed at the joints of the rail sections as these should be all the bolts necessary to prevent the rail sections 125 130

from moving out of position, although the natural expansion and contraction of the rail sections owing to changes of temperature will be permitted without injury thereto or to the tie and fastenings and without danger of causing an accident.

While the preferred embodiment of the invention has been shown and described, it is to be understood that minor changes may 10 be resorted to within the scope of the appended claims without departing from the spirit of the invention.

What is claimed is:

1. A rail tie and fastening comprising a tie body, a binding member for said body and having outwardly directed flanges, a rail supporting plate positioned upon said tie body and having flanges overlapping the outwardly directed flanges of the binding member, means for securing said rail supporting plate in position, and rail clamping members.

2. A rail tie and fastening comprising a tie body, a binding member extended around and embedded in said tie body, said binding member having flanges, a rail supporting plate mounted upon said tie body and clamped to the flanges of said binding member, additional means for securing said rail supporting plate upon said binding member, and rail clamping members positioned in said rail supporting plate and adapted to be secured thereto.

3. A rail tie and fastening comprising a tie body, a binding member embedded in said tie body having outwardly directed flanges, a rail supporting plate positioned upon said tie body and having turned back flanges overlapping the outwardly directed flanges of the binding member, means for securing said rail supporting plate to said binding member, and rail clamping members secured to said rail supporting plate to clamp a rail upon the latter.

4. A rail tie and fastening comprising a tie body, a binding member extending around and embedded in said tie body, said binding member having outwardly extended flanges, a rail supporting plate mounted upon said tie body and having end flanges clamped around the flanges of said binding member, means for securing said rail supporting plate upon said binding member, said rail supporting plate having upwardly

extending side flanges, and rail clamping members positioned in said rail supporting plate and having upwardly directed flanges parallel with and adapted to be secured to the flanges of said rail supporting plate to retain said clamping members in binding engagement with the web the base and the under face of the tread of a rail positioned upon said rail supporting plate.

5. A rail tie and fastening comprising a tie body, means for reinforcing said tie

body, a binding member extended around and embedded in said tie body adjacent the end thereof, means for securing said binding member to said tie body, inclosing and protecting means for the last mentioned means embedded in said tie body, a rail supporting plate mounted upon the end of said tie body, interlocking flanges carried by said rail supporting plate and said binding member, means for securing said rail supporting plate upon said binding member, and rail clamping members carried by said rail supporting plate to clamp the rail upon the latter.

6. A rail tie and fastening comprising a pair of rail clamping members having portions for engagement with the web of the rail from the underface of the tread to the base thereof and inclined portions for engagement with the upper face of the base from the web to the outer edge of the base, the clamping members having their outer edges directed upwardly to form flanges directed upwardly, a base receiving rail supporting plate having upwardly directed side flanges for engagement with the outer faces of the flanges of said clamping member, means for securing together said flanges of the rail supporting plate, and the rail clamping members to securely retain said clamping members in engagement with opposite sides of the rail engaged upon said rail supporting plate, a tie body, and means for clamping said rail supporting plate on said tie body.

7. A rail tie and fastening comprising a tie body, a U-shaped binding member embedded in said tie body, means for reinforcing said tie body, a rail supporting plate positioned upon said tie body, interlocking end flanges for said rail supporting plate and said binding member at opposite sides of said tie, a pair of clamping members for clamping engagement with opposite portions of a rail positioned upon said rail supporting plate, said clamping members and said rail supporting plate having parallel flanges, means for securing together the parallel flanges of said rail clamping members and said rail supporting plate, and means for reinforcing said rail clamping members to retain upstanding portions thereof in parallel relation to prevent movement of the rail positioned therebetween.

8. A rail tie and fastening comprising a rail supporting plate having side flanges directed upwardly and end flanges turned downwardly and inwardly, a tie body, means carried by said tie body for securing said rail supporting plate upon the end thereof, said means having flanges for interlocking engagement with the end flanges of the rail supporting plate, rail clamping members for clamping engagement with a rail positioned upon said rail supporting

plate, said rail clamping members having flanges upstanding at their outer edges for engagement with the upstanding side flanges of the rail supporting plate, means for securing together the flanges of said rail clamping members and said side flanges of said rail supporting plate, said rail clamping members having perforated rail web engaging portions extended to either side to receive securing members extended through

the web of the rail to prevent longitudinal movement of the rail upon said rail supporting plate.

In testimony whereof I affix my signature in presence of two witnesses.

IDA N. CAREY.
